MANUAL UNSHIFT MECHANISM

William M. O'Neil, Oak Park, Ill., assignor to Teletype Corporation, Chicago, Ill., a corporation of Delaware

Application October 16, 1947, Serial No. 780,222

5 Claims. (Cl. 178—27)

1

This invention relates to printing telegraph apparatus and more particularly to attachments for receiving telegraph printers.

It has been found frequently that printing telegraph reception, particularly in the case of radio printing telegraphy, is not always reliable. In many cases this poor reception is not the fault of the receiving equipment but rather is due to the inability of the transmitting station to beam the transmissions toward the receiver. When the receiver is aboard ship the inability to use diversity reception also results in many errors in the received copy, and in time of war reception is sometimes poor due to the attempt by the enemy to "jam the air." One of the more frequent errors resulting from these causes is the shifting of the receiver platen to the shift position during a period when the transmitting station is sending lower case signals. When this occurs it is necessary to manually force the platen into lower case position in order that the message will be intelligible.

Accordingly, the primary object of this invention is to provide an attachment for receiving telegraph printers whereby the platen may be automatically unshifted whenever a special key is depressed.

Another object of this invention is to prevent the unshifting of the platen at a time when a shift signal is received.

A further object of this invention is to prevent the selection of the shift function at a time when the special unshifting key is held in a depressed position.

Other objects and advantages of the invention will be apparent and the invention will be more readily understood from the following description when read in conjunction with the accompanying drawing.

A complete description of the printer used to illustrate this invention is given in U. S. Patent No. 1,904,164 to Morton et al., and therefore all elements of the printer which are not necessary for an understanding of this invention have been omitted in the present drawing for the sake of clearness.

Referring now to the drawing a platen frame 11 is supported pivotally at 12 in the main frame of a telegraph printer and carries a rotatable platen 13. A vertical shift link 14 is fastened pivotally to the platen frame 11 by a bolt 15 and is secured pivotally at the other end thereof at 16 to the horizontal arm of a bell crank 17. The bell crank 17 is fastened pivotally at 18 to the main frame of the printer.

2 A tongued end 19 of the bell crank 17 is operably connected to a shift lever 21 which is mounted pivotally by a bolt 22 on a shift lever support 23. An unshift intermediate lever or push bar 24 is connected operably with the shift lever 21 by a bolt 25 and is urged downwardly and rearwardly by a spring 26. Similarly, a shift intermediate lever or push bar 27 is connected operably to the shift lever 21 by a bolt 28 and is similarly urged downwardly and rearwardly by a spring 29.

3 A series of vanes 31, pivotally supported in the main frame of the printer, are adapted to be positioned in a permutation corresponding to the signal received by the printer. An unshift code bar or function lever 32 and a shift code bar or function lever 33 are supported pivotally on a function lever shaft 34 and are urged towards the vanes 31 by function lever springs 35 and 36 respectively. The unshift function lever 32 is provided with a horizontal arm 37 which cooperates with and raises the unshift push bar 24 when the unshift function has been selected. A similar horizontal arm 38 on the shift function lever raises the shift push bar 27 when the shift function has been selected.

4 A function bail 41 is mounted pivotally on a shaft 42 and is continuously urged in a clockwise direction about the shaft 42 by a function bail spring 43, whereby a function bail cam follower 44 is continuously held on a function bail cam 45 mounted on a rotary shaft 46 which for the purpose of this invention may be considered as the shaft 76 shown in Fig. 7 of the aforementioned U. S. Patent No. 1,904,164, issued to Morton et al. A function lever bail roller 47 secured to a printing bail (not shown) and movable therewith normally engages the rear vertical arms of the function levers 32 and 33 to hold the function levers 32 and 33 away from the vanes 31. As a printing bail cam follower (not shown) rides up the high portion of a printing bail cam (also not shown) the function lever bail roller 47 drops allowing the function lever corresponding to the selected permutation of vane positions, to pivot about the shaft 34 and thereby raise the corresponding push bar. At this time the function bail 41 pivots counterclockwise around the shaft 42 and a function bail blade 48 moves rearwardly engaging a latch or shoulder 49 on the selected function push bar to move this push bar rearwardly to perform the selected function.

5 Mounted pivotally in the printer base on a shaft 51 is a key lever 52 having a special key 53 thereon. The key lever 52, when depressed, cooperates with and pivots a bell crank lever

54 on a shaft 55. The bell crank lever 54 is provided with an unshift push bar lifter 56 which is adapted to engage an extension 57 on the unshift push bar 24 when the key 53 is depressed to thereby raise the unshift push bar 24 so that the latch 49 thereon will be engaged by the function bail blade 48 during the next rearward movement of the function bail blade 48. The bell crank lever 54 is also provided with a blocking portion 58 which is adapted to move in front of the shift function lever 33 when the key 53 is depressed. If, however, the shift function has been selected on the vanes 31, at the time the key 53 is depressed the shift function lever 33, now being free to do so, will have pivoted forward to a position where it blocks the movement of blocking portion 58 which prevents the unshift push bar lifter 56 from raising the unshift push bar 24 and thus prevents the simultaneous engagement of the shift and unshift push bars with the function bail blade 48. If the key 53 is depressed before a shift signal has been received but is continuously held depressed until a shift signal is received the blocking portion 58 is in front of the shift function lever 33 which prevents the selection of the shift function lever and also prevents the simultaneous engagement of the shift and unshift push bars. This will cause the printer to type in lower case during a period when it should be typing in upper case, but the number of upper case signals received is ordinarily very small relative to the number of lower case signals received so therefore the number of errors in the copy due to this cause will be very small.

When the platen 13 is in shift position at a time when it should be in unshift position the depression of the special key 53 results in the actuation of push bar 24 during the next rearward movement of the function bail blade 48, through mechanism hereinbefore described, which pivots the shift lever 21 clockwise, which in turn pivots the bell crank 17 counterclockwise to thereby raise the vertical shift link 14, which causes the platen frame 11 to pivot at 12 and thereby move the platen downwardly to unshift position.

By this invention there is provided a very efficient and economical attachment for facilitating the manual unshifting of the platen of a receiving telegraph printer. It is contemplated and is within the realm of this invention; when the copy is primarily upper case signals, that the shift function push bar will be operable by the special key on the printer base.

Obviously other changes and modifications may be made in the invention without departing from the spirit thereof.

What is claimed is:

1. In a telegraph printer, a plurality of function performing means, each of said function performing means being responsive normally to a signal corresponding thereto to cause a corresponding function to be performed, a special key, a lever operable when said special key is depressed for normally engaging one of said function performing means to cause it to perform its specified function, and means on said lever for engaging a second function performing means when a signal corresponding to said function performing means has been received to prevent said lever from engaging said first function performing means.

2. In a receiving telegraph printer having a shiftable platen, means for shifting said platen, means for unshifting said platen, a lever responsive to the depression of a key for normally en-

gaging said unshifting means to cause the unshifting of said platen, and means on said lever for engaging said shifting means when a shift signal has been received to block the further movement of said lever and thereby prevent the unshifting of said platen when a shift signal has been received.

3. In a receiving telegraph printer, a shiftable platen, means for shifting the platen including a shift function lever and shift push bar, means for unshifting the platen including an unshift push bar, a reciprocable function bail for actuating said push bars when in engagement therewith to thereby cause the platen to be shifted or unshifted, a special depressible key mounted on a pivotal key lever, a bell crank lever adapted to be pivoted when said key lever is depressed to normally move the unshift push bar into engagement with said function bail, and blocking means on said bell crank lever adapted to engage said shift function lever when the shift function lever is actuated in response to a shift signal to move the shift push bar into engagement with the function bail, whereby said bell crank lever is prevented from moving the unshift push bar into engagement with the function bail.

4. In a telegraph printer, a plurality of permutatable members adapted to be permutably positioned in accordance with a signal received by the printer, a plurality of selectable code bars cooperating with said permutatable members and adapted to be moved into selected position when a corresponding permutation of said permutatable members occurs, a plurality of intermediate levers each adapted to be moved into operable position when a corresponding selectable code bar is moved into selected position, means for operating said intermediate levers when moved into operable position, a manually operable lever for moving one of said intermediate levers into operable position, and means on said manually operable lever for blocking from selection one of said selectable code bars corresponding to a second intermediate lever to prevent the simultaneous movement and operation of more than one of said intermediate levers.

5. In a telegraph printer, a plurality of permutatable members adapted to be permutably positioned in accordance with a signal received by the printer, a plurality of selectable code bars cooperating with said permutatable members and adapted to be moved into selected position when a corresponding permutation of said permutatable members occurs, a plurality of intermediate levers each adapted to be moved into operable position when a corresponding selectable code bar is selected, means for operating said intermediate levers when moved into operable position, a manually operable lever for normally moving one of said intermediate levers into operable position, and means on said manually operable lever for engaging a selected one of said plurality of selectable code bars to arrest the further operation of said manually operable lever and prevent the simultaneous movement and operation of more than one of said intermediate levers.
